UNITED STATES PATENT OFFICE.

JOHN W. ANDERSON, OF LANCASTER, PENNSYLVANIA.

DAMPER.

SPECIFICATION forming part of Letters Patent No. 691,738, dated January 28, 1902.

Application filed February 2, 1900. Serial No. 3,708. (No model.)

To all whom it may concern:

Be it known that I, JOHN W. ANDERSON, a citizen of the United States, residing at Lancaster, in the county of Lancaster and State 5 of Pennsylvania, have invented certain new and useful Improvements in Dampers; and I do hereby declare the following to be a full, clear, and exact description of the invention, such as will enable others skilled in the art to 10 which it appertains to make and use the same.

This invention relates to improvements in dampers for stovepipes.

The main objects of my present invention are to produce a section of stovepipe containing a damper of simple and practicable construction that is thoroughly adapted to all flues and which may be conveniently and effectually operated to control the drafts thereof, thereby resulting in a saving of fuel consumed.

Various other objects and advantages of the invention resulting from the novel construction of my invention will hereinafter appear; and the invention consists in certain features 25 of construction and combinations of parts more particularly described, and pointed out in the appended claims.

Referring to the drawings, Figure 1 is an elevation, and Fig. 2 a vertical longitudinal 30 sectional view, of a stovepipe-section-provided with a damper constructed in accordance with my present improvements, the device being illustrated as closed. Fig. 3 is a top plan view of the section thus provided, the damper being shown closed with its register open. Fig. 4 is a view similar to Fig. 1, viewing the section from the opposite side. Figs. 5 and 35 6 are details of parts hereinafter referred to.

Similar numerals of reference indicate similar parts in all the figures of the drawings.

As in my previous patents in this class of inventions, I prefer to assemble the parts composing the same in a short section of pipe 1, the latter being either formed of sheet metal 45 or cast, as preferred, and designed to be joined to the adjacent ends of two stovepipe-sections, all as usual. If preferred, however, it will be obvious that my invention may be constructed in or applied to any ordinary flue.

Above the point within the section 1 where the damper mechanism hereinafter described is located I may form the said section with a

pair of parallel annular ways or beads 2, between which at intervals I produce cold-air openings or inlets 3. Seated between the 55 ways or beads 2 and adapted to revolve over the openings 3, so as to open or close the same, either wholly or partially, is a band, or it may be a slide-plate 4, the same being designed for operation by hand or by automatic 60 mechanism hereinafter referred to. The object, of course, is to admit cold air above the damper, thus breaking the draft or arresting the same and preventing the consumption of fuel while at the same time serving to carry 65 off the gases.

The section is at diametrically opposite sides provided with bearing-openings 5 at points below the cold-air inlets referred to, and in the same are mounted for rotation the 70 journals 6 and 7 of an annular damper frame or ring 8. The damper ring or frame 8 is formed with segmental draft-openings 9 and with a central opening 10, the latter being occupied by a stem 11, axially disposed, extending at opposite sides of the frame or ring, oppositely threaded and held in position by means of clamping-nuts 12 or other suitable means. Near its opposite ends and arranged adjustably thereon are located baffle-plates 13. 75

The rear journal 7 of the damper-frame or ring 8 is formed in the present instance with a cavity 14, in the bottom of which is located an internally-threaded stud 15. A hub 16 surrounds that portion of the journal 85 lying outside the section 1, and is provided on its upper side with a toothed sector 17, the teeth of which engage with a toothed segmental plate 18, either secured to or formed as a part of the band 4. A thumb-screw 19 passes through an aperture in the hub 16 and enters the internally-threaded stud 15, thus confining the hub in position relative to the toothed segment 18 against the expanding tendency of a coiled spring 20, which surrounds the said stud and is interposed between the adjacent surfaces of the hub and the bottom of the cavity 14. It will be obvious that when the parts are thus arranged a partial rotation of the damper frame or ring, 90 so as to bring the same to a closed or horizontal position, will cause an automatic opening of the cold-air openings, or a partial closing of the damper will cause a relatively partial

opening of said openings. It will be further observed that where it is undesirable to utilize the cold-air openings, as would be the case with some flues, a loosening of the thumb-screw 19 would permit the expanding spring 20 to force the hub outward, thus disengaging its teeth from those of the plate 18, whereby the latter and the band 4 will remain undisturbed, and may therefore be either operated by hand or remain inactive.

Mounted rotatably upon the stem 11 at opposite sides of the valve frame or ring 8 are the three-leaved register-valves 21, each leaf of which is slightly greater than one-half the area of each of the openings 9, so that when the said registers are rotated in opposite directions the leaves thereof combine to either partially or wholly close the openings 9. It is the ordinary practice in this class of dampers to use but a single register, the leaves of which are slightly greater in area than are the openings. This arrangement has been objected to, inasmuch in many instances it caused too great restriction of the draft. By the present arrangement, however, I am enabled to greatly increase the size of the openings 9, and thus commensurately increase the draft. I deem this to be one of the important features of my invention, irrespective of the means now to be described for operating the registers.

The journal 6 of the damper frame or ring is hollow or tubular, projects through and beyond the bearing-opening 5 in the pipe-section 1, and has formed at its rear end an annular bead or flange 22.

23 designates a lever for operating or rotating the damper ring or frame 8, and the same is removably mounted on the tubular journal 6 in any suitable manner. In the present instance the said lever 23 is provided at its inner end with a hub or ring 24, provided in turn with diametrically opposite internal lugs or ribs 25, which latter engage with corresponding grooves 26, formed exteriorly in the tubular journal 6. The outer or free end of the lever 23 may be provided with a knob for operating the same.

The hub or ring 24 is of somewhat less width than the tubular bearing 6, and therefore the latter projects slightly beyond the former, and it in the present instance extends through a central opening 27, formed in a dial-plate 28, secured fixedly in the present instance to the section 1 by means of rivets 29. This dial-plate may be divided in any convenient manner, the degrees being indicated in the present instance by numerals ranging from "0" to "12," and at the top 60 may appear the word "Medium," while at the bottom at opposite sides of the zero-point may appear the words "Open" and "Closed."

A rock-shaft 30, slightly longer than the tubular bearing 6, may be loosely journaled in the said bearing, and therefore will extend beyond the opposite ends of the same. At its outer end there is mounted on shaft 30 an

indicator or hand 31, designed to move over the dial 28 and be brought against either side of a stop-lug 32, located at the zero-point of the dial. This indicator or hand is maintained in position in the present instance by means of a screw 33, the head of which overlaps the hub of the indicator and the point of which enters an aperture in the outer end 75 of the shaft 30.

At the inner end of the shaft 30 there is mounted a small pinion or spur gear 34, which latter may be either formed integral with the shaft or secured thereto by any suitable means, and engaging the teeth of this gear at diametrically opposite sides are toothed segmental arms or rack-bars 35, one of which extends from each of the register-plates 21 and which are disposed in opposite directions. These segmental arms or rack-bars may be maintained in operative engagement with the aforesaid gear by means of a guide or keeper 36, the same having a somewhat U shape and being located on the shaft 90 30 between the flange 22 of the tubular journal 6 and the gear-wheel 34.

It will be observed that, as before stated, the damper as a whole is rotated by means of the lever 23, and likewise will the cold-air 95 openings be opened and closed by the same mechanism. The register, however, can be operated by means of the indicator 31, which when moved over the dial rotates the rock-shaft 30 and with it the gear-wheel 34, thus causing the segmental rack-bars or arms 35 to travel in reverse directions and moving the leaves of the opposing register-plates toward or away from each other, thereby opening or closing either partially or wholly the openings 9 of the damper.

It is well-known that no two flues are exactly alike, some requiring a great deal of draft and others very little. By experimenting with my invention when placed in any flue one will soon learn how to obtain the very best results and by means of the dial can always adjust the parts to their proper positions.

Having described my invention, what I claim is—

1. The combination with a damper frame or ring, provided with radial register-openings; of registers axially swiveled in different planes at opposite sides of the said frame or ring, and provided with radiating leaves each of which is of an area equal to about one-half of each of said register-openings.

2. The combination with a damper frame or ring, provided with radial register-openings; of registers axially swiveled in different planes at opposite sides of said frame or ring, and provided with radiating leaves each of which is of an area equal to about one-half of each of said register-openings; and means for moving said registers in opposite directions.

3. The combination with a stovepipe-section; and a damper frame or ring journaled rotatably therein and provided with segmen-

- tal radiating register-openings; swiveled at opposite sides of the ring and in different planes and registers having radiating segmental leaves for said openings and located at opposite sides of said frame or ring, the leaves of said registers being of less area than that of the said openings; and means for rotating the said damper frame or ring and rotating the registers in opposite directions.
10. 4. The combination with a stovepipe-section; and a damper frame or ring journaled rotatably therein and provided with radiating register-openings; of opposite registers located in different planes at opposite sides of the said frame or ring, and provided with leaves for the openings of less area than the same and with oppositely-disposed rack-arms arranged in different planes; a pinion gearing with the said arms located between the same and carried by the journal of the frame or ring; and means for rotating the same.
5. The combination with a stovepipe-section; and a damper frame or ring journaled rotatably therein and provided with radiating register-openings; of registers located in different planes and at opposite sides of the said frame or ring, and provided with radiating leaves for said openings and of less area than the same, and with oppositely-disposed 25 rack-arms; a pinion arranged intermediate and gearing with the said arms and carried by the journal of the damper-frame; means for rotating the damper-frame as a whole; and independent means for rotating said pinion.
30. 6. The combination with a stovepipe-section; and a damper frame or ring journaled rotatably therein, and provided with radiating register-openings; of registers located in different planes and rotatably mounted at opposite sides of the said damper frame or ring and having radiating leaves of less area than that of the openings; oppositely-disposed rack bars or arms carried by the registers; a pinion arranged intermediate of and gearing 45 at opposite sides with the same, and supported by the journal of the damper-frame; a keeper supported by said journal and loosely engaging the arms or bars; and means for operating the damper frame or ring; and means for 50 rotating the said pinion.
7. The combination with a stovepipe-section; a damper frame or ring having radiating register-openings and a hollow journal located therein; and an operating-lever mounted on the outer end of said hollow journal; of registers arranged in different planes and rotatably mounted at opposite sides of and carried by the damper-frame, and provided with radiating leaves of less area than the openings 55 in said frame or ring; oppositely-disposed rack-arms extending from said registers; a shaft journaled in the hollow journal; a pinion at the inner end of the shaft arranged intermediate of and engaging the rack-bars; an 60 indicating-hand at the outer end of the shaft;

and a dial over which said hand is adapted to move.

8. The combination with a stovepipe-section; a damper frame or ring having register-openings, and a hollow journal located therein, the outer end of said journal being externally grooved; an operating-lever therefor, the same being provided with a hub having ribs to interlock removably with said grooves of the journal; a stationary dial fitted over the outer end of the journal and serving to retain the said operating-lever thereon; a shaft loosely mounted in the journal and extending beyond the ends thereof; an indicating-hand on the outer end of the shaft adapted to move over the said dial; a pinion on the inner end of the shaft and adapted to move therewith; and a U-shaped guide carried by the shaft; of registers pivotally mounted at opposite sides of the damper ring or frame, and provided with leaves of less diameter than the register-openings; and rack-arms extending in opposite directions from the said registers, engaged by the said pinion and passing between the same and the said guide.

9. The combination with a pipe-section provided with cold-air openings; and a slide for closing the same; of a rotatable damper at a point below the openings; a toothed segment loosely mounted on one of the axes of said damper and adapted to rotate therewith; a rack-bar carried by the slide; a spring for normally pressing the segment out of alignment and engagement with the teeth of the rack-bar; and means for preserving such engagement against the tension of said spring.

10. The combination with a pipe-section, provided with cold-air openings; and a slide for the same; of a damper rotatably mounted in the section below the openings; means for operating the damper; a rack-bar carried by the slide; a toothed segment for engaging the same carried by one of the journals of the damper; and a yielding connection between said toothed segment and said damper whereby the former may be thrown into and out of engagement with the rack-bar.

11. The combination with a pipe-section having a series of cold-air openings; and a slide for the same; of a damper journaled in the section below the openings; means for rotating the damper; means carried by the damper-journal for operating the slide; and a yielding connection between said slide-operating means and said damper whereby the former may be thrown into and out of operation.

In testimony whereof I have signed my name to this specification in the presence of two subscribing witnesses.

JOHN W. ANDERSON.
